UNITED STATES PATENT OFFICE.

ELIJAH D. McDONALD, OF LOS ANGELES, CALIFORNIA.

DEEP-WELL PUMP.

1,422,588.

Specification of Letters Patent. Patented July 11, 1922.

Application filed February 2, 1921. Serial No. 441,920.

To all whom it may concern:

Be it known that I, ELIJAH D. McDONALD, a citizen of the United States, residing at Los Angeles, in the county of Los Angeles 5 and State of California, have invented new and useful Improvements in Deep-Well Pumps, of which the following is a specification.

This invention relates to pumps, and particularly pertains to deep well pumps of the screw impeller type.

An object of the invention is to provide a pump of simple construction and high mechanical efficiency.

15 Another object is to provide a construction embodying a plurality of interchangeable parts that may be assembled to provide a pump for lifting water or oil from a well of any given depth.

20 Another object is to provide a construction in screw impeller pumps whereby a flow of water is directed against each impeller in such a manner as to tend to avoid contacting with the outer perimeter of the impeller so 25 as to reduce the slippage common to this type of pump.

Another object is to provide a member adapted to be interposed between each section of casing immediately below the impeller. This member being adapted to serve 30 as a means for rigidly securing the sections of casing together so as to be water-tight; to provide a rigid guide for the impeller shaft; to provide a stuffing box or similar means 35 encompassing the shaft so that grit or foreign articles will not come in contact with the shaft at that point; and to further provide a means for directing the flow of fluid therethrough to prevent slippage.

40 Another object is to provide, in such pumps, a bearing disposed within a watertight compartment at the base of the pump, to serve jointly as a thrust bearing and as a guide to prevent whipping of the lower end 45 of the shaft. This bearing being completely enclosed to exclude grit and foreign particles which might otherwise enter.

Another object is to provide a means of thoroughly lubricating all bearings in 50 pumps of this type.

A further object is to provide a pump particularly adapted for lifting crude oil from wells, and a means for breaking up and dis-

solving paraffin and other matter that normally tends to choke up the suction end of 55 oil pump and interfere with pumping the oil.

Other objects will appear hereinafter.

The invention is illustrated in the accompanying drawings, in which:

Figure 1 is a view mainly in vertical section of a pump adapted to carry out the purpose of the invention; those portions in which parts shown are duplicated not being shown.

60 Figure 2 is a view in section as seen on the line 2-2 of Figure 1.

Figure 3 is a view in section as seen on the line 3-3 of Figure 1.

Figure 4 is a view in section as seen on 70 the line 4-4 of Figure 1.

Figure 5 is a view in section as seen on the line 5-5 of Figure 1.

Figure 6 is an enlarged detail view of a 75 portion of the pump casing.

Figure 7 is a view in section as seen on the line 7-7 of Figure 6.

More specifically, 8 indicates a vertical shaft driven in any suitable manner, but here shown as provided with a pulley 9 for 80 this purpose which is guided at its upper end by a yoke 10. This shaft is shown extending vertically through the center of a pump casing 11, which casing is made up of a plurality of casing sections 12. Disposed at the lower end of each section of casing are screw impellers 13 of the Archimedean type, which are fixed to the shaft and rotated thereby and which normally are of a circumference sufficiently less than the 90 inner perimeter of the casing in order to give sufficient clearance and provide for wearing of the parts. The shaft is supported by thrust bearings 14 and 15 disposed above the surface of the ground which may 95 be of any suitable type or number, but are here shown as being two in number. The upper bearing 14 is of the usual oblique roller type and serves to practically support the weight of the shaft as well as serving 100 as a centering means therefor. This roller bearing is supported by a circular casing 16 which completely encloses it and is formed with a circular pocket 17 in which the roller bearing rests. This pocket is provided with 105 a cover 17 at its upper end and is also pro-

vided with a stuffing box 18 rendering the pocket practically oil tight and proof against dust and foreign matter. To the external casing 16 is bolted a discharge casing 19 of somewhat similar construction, which is provided with a water discharge pipe 18'; the upper wall of this discharge casing is formed with another circular pocket 19' in which is disposed a plurality of thrust washers 20 which encompass the shaft, but permit of free rotation thereof. Positioned immediately above these washers is a thrust collar 21 which is fixed to the shaft and which rests upon the upper of the washers 20. This pocket is also provided with a packing gland similar to that provided for the upper thrust bearing to render the circular pocket oil tight so that the thrust washers may be lubricated.

20 The general arrangement of shaft, casings, impellers, and thrust bearings as described or those substantially similar are common to these types of pumps and are well known. It will be observed, however, 25 that the lower thrust bearing which is normally designed to take the greatest portion of the load is so disposed within the discharge casing as to be completely surrounded by the flowing water, and thus be 30 kept cool as is essential for such bearing. The upper bearing may also be cooled in a similar manner by causing some of the discharge to pass through the upper casing. In the construction of the casings 16 and 19 35 a single piece serves as a casing as well as a support for thrust bearings.

Other features new and novel to deep well pumps is a steam passage 22 which extends downward through the shaft, the shaft being 40 formed hollow to provide this passage. Steam is admitted to this passage through a plurality of radial ports 23 which are provided in an enlarged portion 24 of the shaft which may be formed thereon in any suitable 45 manner, but is here shown as screwed thereto. This enlarged portion 24 is surrounded by a fluid-tight casing 25 which closely surrounds all exposed surfaces thereof and which further assists in supporting 50 the weight of the shaft and to take up some of the thrust. This casing is provided with a steam inlet port 26 which extends partially around the circumference thereof so as to establish communication with the hollow 55 portion of the shaft and which port 26 extends over a sufficient arc so that steam is always being admitted to at least one of the radial ports to provide an uninterrupted flow of steam and an equalization of pressure 60 throughout all steam passages. This casing is provided with a cover portion 27 which is secured thereto in any suitable manner, such as by cap screws 28 and which may be fixed so as to frictionally engage the 65 upper surface of the enlarged portion of the

shaft. A lubricant supply pipe 29 passing externally of the casing to a suitable source of lubricant, not shown, is adapted to supply lubricant to the rubbing surfaces within the casing and to render parts steam tight. A 70 lubricant discharge line, not shown, may be also provided to carry off the excess lubricant and to permit of constant circulation. Surrounding this casing is another casing 30 of larger diameter which provides a 75 water passage around the inner housing, this casing being provided at its upper end with a flange 31 secured thereto and bolted to the casing 19 and is further provided at the lower end with another flange 32 to which 80 is secured the upper section of the pump casing. This arrangement of flanges and casings being adapted to permit of the ready assembly or repair and replacement of the parts contained therein. The upper 85 impeller is disposed at any suitable depth below the ground according to the conditions, and the upper section of the casing may be of any suitable length or consist of a plurality of sections joined together in 90 any suitable manner, but is here shown of comparatively short length so that this upper impeller is immediately below the surface of the ground.

The impellers jointly known as a cluster, 95 are preferably disposed singly in each section of the casing, as is common to this type of pump. These sections are joined together and held rigidly relative to one another by means of a circular member 33 100 which constitute a new and novel element in pumps of this type. This circular member which as shown clearly by Figures 6 and 7, is of larger diameter than the casing sections and is provided with a plurality of 105 bolt holes 34 spaced around that portion thereof which is external to the casing. The upper and lower surfaces of this circular member are each provided with an annular recess 35 adapted to receive the adjacent 110 ends of the casing sections to tend to hold them rigidly in position and to provide a fluid-tight joint.

In the assembly of the pump, the impellers are fixed to the shaft so as to be positioned immediately above the circular member. Bolts 36 of sufficient length to pass from the upper surface of one circular member to the lower surface of the member positioned below it are then inserted through 115 the holes provided. These bolts are alternated so that alternate bolts extend upward to engage the lower flange so that two adjacent circular members are rigidly bolted together and the lower of these two circular flanges is in turn rigidly bolted to the underlying member. This construction permits of building up a casing of any required length, of a plurality of casing sections, all 120 of which are substantially the same and 125 130

interchangeable and each circular member is also similar and interchangeable with the other.

Shaft guide-bearings 37 of suitable material such as bronze are inserted within these circular members which are recessed to receive a shoulder 38 formed on the guide-bearing. The circular members are internally threaded to receive packing glands 39 which closely encompass the bearings 37 and provide a means of retaining packing 38' in position around the shaft. These packing glands are preferably made of the same material as the guide-bearings and the lower portion 39' of each is formed to serve as an additional guide-bearing for the shaft. The glands are provided with threads 40 whereby they may be screwed into position and retained thereby by the normal rotation 20 of the shaft, the threads being such that the tendency of the gland to turn with the shaft results in the packing being at all times tight and compensating for its normal wear.

The packing serves to prevent grit and foreign matter from coming in contact with the guide bearings. These guide-bearings may be positioned at suitable intervals throughout the entire pump unit and when the casing sections are of short length it is not essential to provide such a bearing in each circular member.

These circular members are provided with segmental openings or water passages 41 which are formed by radial ribs 42. The outer perimeters of these segmental water passages are preferably circular and disposed in an arc of lesser circumference than the inner perimeter of the casing, and which arc is also within the outer perimeter of the impeller. These water passages thereby direct the flow of water passing therethrough and tend to prevent water from coming in contact with the outer perimeters of the impeller, resulting in a reduction of slippage as has been found in practice. The ribs 42 also serve to reduce the swirling action of the water, the reduction of which, as is well known, also tends toward improved efficiency.

It will be observed that the circular members which are of simple construction serve to provide a means for quickly and securely assembling a plurality of interchangeable sections of casing together to form a rigid pump casing of any required length; to serve as a means for directing the flow of water so as to reduce slippage in the manner described; to provide a rigid guide and bearing for the shaft; to provide a stuffing box to prevent grit and foreign matter from coming in contact with the shafts and to permit of the assembly of a complete unit in which a shaft and casing are held rigidly relative to one another.

The lowermost circular member placed at

the suction end of the completed pump is inverted and its under surface is provided with an annular recess 43 of smaller diameter to receive a smaller casing 44 which completely surrounds the shaft, so as to provide a fluid-tight compartment 45 for a thrust bearing 46. A lowermost member 47 holds a stationary portion 48 of the thrust bearing 46 which is also drilled to provide a continuation of the steam passage, the normal contact of the rotating shaft and the stationary element of the bearing serving to provide a steam tight joint. This stationary portion 48 is formed convex at its upper end to engage the shaft which is formed concave at its end. Screwed to this stationary member 48, which projects downward through the lowermost member 47, is a steam discharge cage 49 which is closed at the bottom to retain a spring balanced check ball 50 which prevents the contents of a well from entering the hollow shaft.

Openings 51 are provided in this cage to allow the steam to escape. In pumping oil from wells the steam serves to loosen and dissolve paraffin and other precipitations which form about the suction cages of oil pumps, thus assuring a steady flow of oil.

Lubrication of all bearings is effected by forcing lubricant into the hollow shaft either with the steam or separately at suitable point, such as at the upper thrust bearing. The shaft is provided with small openings 52 which may be positioned at any point that it is desired to have the oil enter or escape. Overflow of the lubricant from the upper thrust bearing or other points at which it is admitted will pass through these openings and due to centrifugal force will be held against the internal wall of the hollow shaft and will escape at the openings provided and thus lubricate all surfaces wherever the openings are provided. By forcing oil into the upper thrust bearing at a pressure greater than that of the steam this oil will lubricate those bearings and then enter the hollow shaft and flow downward to lubricate any predetermined bearings. This flow of oil will result in the lower thrust bearing disposed at the bottom of a well being thoroughly lubricated, the lubricant being retained therein by the fluid tight casing around it.

The operation of the pump is apparent from the foregoing, rotation of the shaft causing the screw impellers to lift the water or oil in the manner well known, but in the operation of pumping water, steam is not admitted to the shaft but lubrication is effected by the hollow shaft in either of the operations.

While I have shown and described a specific embodiment of my invention, I do not limit myself to the exact details of construction and the arrangement of parts shown,

but may employ such changes and modifications as occasion may require without departing from the spirit of the invention, coming within the scope of the appended 5 claims.

I claim:

1. In a pump, the combination of a rotatable shaft having a steam passage extending downward through said shaft, means 10 for admitting steam thereto, screw impellers on said shaft, a casing surrounding said shaft and impellers and comprising a plurality of casing sections, circular members disposed between said sections and having 15 an annular shaft guide supported by said circular members, packing means on said guide, means for securing each circular member to adjacent circular members, said members provided with water passages having 20 their outer perimeter of lesser radius than the screw impellers, a suction cage fixed to the lower end of said casing, a water-tight compartment within said casing, a thrust bearing disposed within said suction cage 25 and adapted to center such shaft.
2. In a pump, the combination of a rotatable shaft having a steam passage extending downward through said shaft, means for admitting steam to said rotatable shaft, 30 screw impellers on said shaft, a casing surrounding said shaft and impeller; said casing comprising a plurality of sections, circular members disposed between said sections and having an annular recess on either 35 surface to receive the adjacent ends of said casing, shaft guides supported by said circular members, stuffing boxes to said shaft guides, means for securing each circular member to the adjacent circular member; 40 said circular member further provided with water passages having their outer perimeters of lesser radius than said screw impellers, a suction cage fixed to the lower end of said casing, a thrust bearing disposed within said 45 suction cage adapted to center said shaft, and a water tight casing surrounding said bearing.
3. In a pump having a rotatable shaft and a plurality of impellers fixed thereto, the 50 combination of a plurality of section casings

surrounding said shaft and impellers, and circular members of larger diameter than said casing disposed between said sections of casing, said circular member having a shaft guide portion fixed thereto and formed with 55 a packing gland, and further provided with a plurality of water passages adapted to direct the flow of fluid through said pump whereby the water tends to avoid the outer perimeter of said impeller, and means for 60 securing each of said circular members to adjacent members.

4. In a pump having a vertical rotatable shaft, the combination of a suction cage, a shaft guide adapted to center said shaft and receive some of the thrust thereof, said shaft guide secured to said intake cage, and a fluid tight casing surrounding said shaft 65 guide.

5. In a pump having a rotatable hollow 70 shaft, means for admitting steam to said shaft, said means comprising a plurality of steam ports radially positioned in said shaft, a stationary steam tight casing closely encompassing said shaft formed with a steam 75 port therein adapted to be in constant communication with at least one of said radial steam ports at all times.

6. In a pump, a tubular shaft, an end 80 thrust bearing for said shaft, and a housing enclosing the point of contact of the shaft and thrust bearing forming a water tight chamber around the shaft, said shaft formed with an opening through which lubricant may be delivered from the interior of said 85 shaft by centrifugal force.

7. In a pump, a tubular shaft, a thrust bearing for the end of said shaft having a passage communicating with the interior of 90 said shaft, said bearing having a concave end wall and said shaft having a convex end seating on said wall, and a housing enclosing the point of contact of the shaft and thrust bearing forming a water tight chamber around the shaft, said shaft formed with 95 an opening through which lubricant may be delivered from the interior of said shaft by centrifugal force.

ELIJAH D. McDONALD.
